UNITED STATES PATENT OFFICE

2,428,468

TRACKS FOR MODEL RAILWAYS

Thomas Pinder, Scarborough, England

Application November 10, 1943, Serial No. 509,793
In Great Britain December 11, 1942

10 Claims. (Cl. 238—10)

1

This invention relates to flexible tracks for model railways, or models that run on rails, of the type comprising laterally flexible rails interconnected by cross-ties or sleepers for maintaining the gauge, the arrangement being such that the track can be flexed laterally into either a plain or a sinuous curve.

In order to maintain the correct gauge when the track is curved it is necessary to have the cross-ties or sleepers disposed radially with respect to the curve and in my prior British Patent No. 542,521 this arrangement is obtained in one particular manner. Such specification states that all the cross-ties or sleepers are permanently and rigidly connected to one of the rails, not necessarily all to the same rail, and all of them are connected to the other rail or rails so as to be capable of movement lengthwise thereof, with the possible exception of one cross-tie or sleeper in a track length, usually the centre-one, which may be permanently and rigidly connected to both or all the rails so as to serve as an anchorage which prevents relative longitudinal displacement of the rails.

When a track is curved it is obvious that the ends will not be in radial line as the outer rail will follow a greater curve than the inner rail and it is the main object of the present invention to overcome this difficulty.

Accordingly this invention is characterised in that any desired rail of a track section is furnished with a movable joint (or joints) formed by overlapping the ends of two lengths of rail intermediate the ends of the section with connecting means for holding the joint and affording relative movement between said overlapping ends when the rail is flexed so that it extends or contracts automatically in length.

This construction enables the ends of rails forming a track section to be connected in fixed transverse relation to each other so as to be in a radial line when the track is curved and all sections will fit together automatically irrespective of their formation.

Moreover the movable joint may comprise a half lapped or tapered scarf joint with one or more connecting elements for maintaining the joint and affording any relative movement caused by flexing the rails.

According to a feature of the invention a joint includes at least one flexible joint member located against the webs of the rail ends to span any gap on its immediate side formed by flexion of the rails. Such member may provide connecting elements for maintaining connection at the joint.

2

All the connecting elements may comprise clips which embrace the bottom flange or edge of a rail and such clips may be on the rails and/or the cross-ties or sleepers and/or on the joint member when employed.

Referring now to the accompanying drawing in which embodiments of the invention are shown by way of example only:

Figs. 1 and 2 are respectively a side and plan view of a half lap joint with a joint member on one face;

Figs. 3, 4 and 5 are respectively sections on lines A, B and C, of Fig. 1;

Fig. 6 is a sectional view of a modified form of joint member;

Fig. 7 is a sectional plan showing a modified simple joint member in position;

Fig. 8 is a perspective view of two rail ends with a double joint member in position to receive such ends;

Fig. 9 is a perspective view of a double joint member with integral flexible clip means;

Fig. 10 is a perspective view of two rail ends adapted to form a taper joint;

25 Fig. 11 is a plan view of the taper joint;
Fig. 12 is a plan view of a straight two-rail track section;

Fig. 13 is a perspective view of a clip for joining track sections;

30 Figs. 14 and 15 are respectively a plan view of a crossing or points section and a crossover section.

In Figs. 1 to 5 the ends 1, 2 of the rails 3, 4, are half lapped in a vertical scarf joint and the upper flanges 5, 6, are cut away below their upper faces on one side for a distance depending upon the total movement required. A joint member 7 of flexible material is fitted against the webs of the rail ends below these cut away parts and held 35 in position by connecting elements comprising clips 8 formed on (or fixed to) the member and adapted to embrace the lower flanges 9, 10, of the rail ends. The rail ends may slide freely in both the clips or the clip on flange 9 may grip it firmly and both rail ends slide in the clip on flange 10. The joint member 7 is of such a thickness that its top outer edge (with respect to the rail) is in line with the side faces of the flanges 5, 6, so that a vehicle wheel 11 passing over the 40 rail joint will have the tread of the wheel supported by at least half the top flange of one of the rails, while the wheel flange will pass from the side face of a rail flange to the joint member 7 and then to the other rail flange. The 45 joint member is arranged on the inside of the rail,

although two could be arranged in combination on the inside and outside of the joint as this tends to maintain a more homogeneous curve when flexed. Moreover, any desired number of clips 8 may be provided and some, or all, of them may be separate from the member 7, e. g., they may be formed on, or carried by, the rails and/or the usual cross-ties or sleepers or be separate clips.

If desired the joint member may be flanged at 7a as shown in Fig. 6 so long as the member is sufficiently flexible. Alternatively, a plain flexible strip may be packed out by a piece 7b as shown in Fig. 7 or such piece could be omitted if the member was made of spring steel (or its equivalent) and sprung out.

In the modified construction shown in Fig. 8, the joint member 12 is of double formation to lie on both sides of the rail joint and its two parts are joined by a centre clip 8a with clips 8 on the ends of the parts. This construction facilitates the holding of the joint whilst allowing the desired freedom of movement and is simply a combination of two of the aforesaid single joint members 7. Where it is desired to provide a long clip or connecting element for a greater extension or contraction of rails, e. g., where the total movement of the rail necessitates an end-wise floating attachment to sleepers to maintain the track gauge, then the construction shown in Fig. 9 may be adopted. The two parts of the member 12 are joined by a long clip 8b which is cut into small sections so that the whole clip is flexible and yet can slide in a clip or equivalent part on a sleeper.

In the alternative construction shown in Figs. 10 and 11, the movable rail joint is formed by a tapered joint, i. e., the ends 1, 2 are tapered to a more or less knife edge and furnished with clips 8 at their toes to maintain the joint and afford the required relative sliding movement. One of the clips 8 may be attached after the joint is made and the third clip 8c can be formed on or attached to a sleeper 13 to keep the gauge of the track. The length of taper of the rail ends is arranged to suit the maximum movement required, the maximum widening of gauge that can be permitted just before the toe of each taper and to permit of keeping the toes of each joint from being opposite each other in any position.

Any number of the above movable joints may be included in a track section whether of the two-rail type shown in Fig. 12 or a three or four or more rail type. With the two-rail track one rail could be fixed to the sleepers and the other rails 3, 4, mounted slidably in relation to the sleepers and furnished with, say, one joint which would allow extension or contraction of the total length of said rails depending upon which way the track is curved laterally. The ends of sections can be joined up in any known manner by connecting the rails and/or sleepers or other parts, and in the drawing each end sleeper 13a, to which the rail ends at the extremities of the section are fixed to retain them in fixed transverse relation to each other, is furnished with a clip fastener 14 (Fig. 13) which is pivoted to a sleeper by a pin 15 so as to drop over contiguous sleepers 13a and hold them together. The pin 15 passes through both of the sleepers and serves to locate the rails in alignment. Furthermore, whilst the rails may be simply butt jointed there may alternatively be a half-lap (or taper) joint at the ends of one or both rails in each section to ensure a more homogeneous curve. Clip means maintain such

a joint. If both rails have movable joints and are mounted slidably in relation to the sleepers then the sleepers are tied together by a further rail 16, which may be the "live" rail in electrified tracks, about which any curves are made and the movable joints of one set of rails will extend whilst on the other side they will contract. The extra rail need not be between the two engine rails or on the top of the sleepers and may form a half-lap (or taper) joint at section ends instead of, or in addition to, the engine rails. In any of the above joints it is preferred that the half laps or tapers in each section of track be facing the same way in order that the gaps may be staggered. Moreover, the above movable joints may serve to join the ends of rail sections together instead of, or in addition to, being arranged intermediate the ends. The combined clip 12 is eminently suitable for this and could be permanently attached to one rail. The track gauge may be maintained at any of the movable joints by the use of one or more clips on the sleeper for receiving the slideable rails and/or joint members, or by attaching one of the aforesaid clips to a sleeper.

Moreover, crossing or points sections may be constructed as shown in Fig. 14 wherein movable joints are provided at the points 17 which affords adjustment for the rails of the diversion tracks 18 and 19 when curved (some or all of these joints may be dispensed with) to a desired form, and the distribution track 20 when moved from one track to the other. This track 20 is moved by mounting a slideable bar 21 in the bearer 22, anchoring the bar to the track rails by pins 23 which slide in a curved slot 24, and providing a rotatable operating element 25.

For crossovers in twin-track sections a similar arrangement is employed except that two bars 21 are used and pivotally anchored to, say, a part of the track, the slots 24 are shown straight (they could be curved) and the element 25 is adapted to pull one bar 21 and push the other to move the required track sections into line. With this arrangement the joint member 12 shown in Fig. 9 would be eminently suitable to afford the desired movement in the rails of the track sections providing the crossover.

In order to retain a proper joint, the distance between clips in which the rails slide is arranged so that they are clear of the gaps when the rails are in any position. Also stops may be provided on the rails to limit movement to the maximum required in either direction.

In the above constructions the standard rail section has been shown and described but any suitable section of rail can be used.

What I claim is:

1. As an article of manufacture, a flexible track section for miniature railways adapted to be connected in end to end relation with other similar track sections to form a complete track, said track section comprising a pair of laterally flexible rails and a plurality of cross ties on which the rails are mounted, one of said rails being a unitary member throughout its length, the other rail having a joint formed by overlapping complementary shaped ends of two lengths of rail intermediate the ends of said track section to permit extension or contraction of the overall length thereof upon lateral flexing of said track section as a unit, means for retaining the ends of said rails in fixed transverse relationship at the ends of said track section and means attaching said cross tie members fixedly to one of said

rails and for sliding movement longitudinally of the other of said rails.

2. As an article of manufacture a flexible model rail track section comprising at least two rail members mounted parallel to each other on cross ties, one of said rails being a unitary member extending from end to end of said section, the other of said rails having a scarf joint intermediate the ends of said section to permit extension or contraction of the length thereof upon lateral flexing of said section as a unit, a flexible connecting element holding the scarf jointed ends of said rail against lateral displacement and slidably engaging at least one of said ends, means for retaining the ends of said rails in fixed transverse relationship at the ends of said track section, and means connecting said cross ties fixedly to one of said rails and for longitudinal slippage relative to the remainder thereof.

3. As an article of manufacture, a laterally flexible model rail track section comprising a pair of wheel bearing rails, a plurality of cross ties on which said rails are mounted, means for attaching said rails to said cross ties in laterally spaced relation while permitting longitudinal floating action with respect to said cross ties, each of said wheel rails having a joint intermediate the ends of said section to permit automatic extension or contraction of the length thereof upon lateral flexing of said section as a unit, a third rail consisting of a unitary member extending from end to end of said track section and fixedly connected to each of said cross ties to form a longitudinal spacing member about which the track section can be laterally flexed as a unit and means connecting the ends of said rails at the respective ends of said section in fixed transverse relation to each other.

4. An article of manufacture as defined in claim 2 in which the flexible connecting element spans the gap where the rail is left incomplete by expansion of said joint.

5. An article of manufacture as defined in claim 2 in which the flexible connecting element is held in place by clip means embracing the lower parts of the rail.

6. An article of manufacture as defined in claim 2 in which the flexible connecting element spans the scarf ends of the joint and has op-

positely disposed clip members engaging the rail on each side of said joint.

7. An article of manufacture as defined in claim 2 in which said flexible connecting element is held in place by at least one clip member engaging the rail adjacent the joint and at least one clip member engaging the scarfed ends of the rail.

8. An article of manufacture as defined in claim 2 in which said flexible connecting element is held in place by clip elements engaging the rail on each side of the joint and the scarfed ends thereof.

9. An article of manufacture as defined in claim 2 in which said flexible connecting element is a flexible channel embracing the lower portion of the rail.

10. An article of manufacture as defined in claim 2 in which the flexible connecting member is secured to the rail by a plurality of clips at least one of which is secured to a sleeper.
